UNITED STATES PATENT OFFICE

MICHAEL J. McCaughey, OF BROOKLYN, NEW YORK

TRAFFIC STANCHION

Application filed January 26, 1931. Serial No. 511,121.

This invention relates to traffic stanchions, and has for an object to provide an improved stanchion adapted to replace stanchions of the type which are now ordinarily set in the roadway during the day and moved to the side of the roadway at night.

It has been found that removable stanchions of the kind referred to above are often tampered with by mischievous boys who set them in a manner to misdirect motorists or who remove them to a distance for the purpose of inconveniencing the person charged with the duty of replacing them in the roadway. Such stanchions, moreover, usually comprise a heavy, solid, concrete base, so that the act of moving them to and from the roadway involves considerable labor and consumes a considerable amount of time.

It is an object of the present invention to provide a stanchion comprising a base, a standard, and an indicator, the standard and indicator being separable into sections, and the base being in the form of a receptacle sunk in the roadway and adapted to receive the standard and indicator parts for storage. The top of the receptacle is desirably arranged to be substantially flush with the surface of the road, and the receptacle is sealed in order to prevent the collection of dirt and water, the rusting of stanchion parts, and the damaging of electrical connections which are desirably provided in the base.

Other objects and advantages will herein-after appear.

In the drawings forming part of this specification:

Figure 1 is a sectional elevation illustrating a stanchion embodying features of the invention;

Figure 2 is a fragmentary, sectional view of a mirror supporting member employed in one of the standard sections;

Figure 3 is a sectional view on the line 3—3 of Figure 1, looking in the direction of the arrows, the structure illustrated being broken away intermediate its ends for compactness of illustration, and having parts broken away for clearness of illustration;

Figure 4 is a detail view, partly broken away, illustrating certain features of con-

struction of the standard sections and indicator;

Figure 5 is a sectional view on the line 5—5 of Figure 4, looking in the direction of the arrows;

Figure 6 is a vertical, sectional view through the receptacle cover of Figure 1, showing the standard replaced by a closure plug;

Figure 7 is a view similar to Figure 3, illustrating another form of stanchion embodying features of the invention;

Figure 8 is a sectional view taken on the line 8—8 of Figure 7, looking in the direction of the arrows;

Figure 9 is a fragmentary, sectional view taken on the line 9—9 of Figure 7, looking in the direction of the arrows; and

Figure 10 is a view similar to Figure 9 and of the same part of the base, but illustrating the standard replaced by a closure plug.

In Figure 1 disclosure is made of a section of roadway comprising the natural earth 1 covered with a layer of concrete 2, the concrete in turn being covered with asphalt 3. A traffic stanchion is illustrated in operative position, the stanchion comprising an indicator 4, a standard 5, and a base 6.

The base is in the form of a receptacle comprising a metal box 7 and a removable cover 8. The box 7 is desirably provided with one or more peripherally extending ribs or flanges 9 embedded in the concrete. The box, at the upper end thereof, is provided with inner and outer upstanding flanges 10 and 11 defining a channel between them, and provision is made of a rabbet 12 at the inner side of the inner flange 10. The channel and the rabbet receive, respectively, continuous downwardly extending flanges 13 and 14 formed on the cover for the purpose of assuring a water-tight seal.

The standard 5 is composed of a plurality of sections 15, 16 and 17. The lowermost section is adapted to be passed for part of its length through an opening 18 formed in the cover 8. The standard section 15 includes a circumferential flange 19 adapted

to rest upon the top of the cover and having an annular flange 20 depending therefrom which is adapted to be received in an annular groove or channel 21 formed in the top of the cover so that a good water-tight connection is secured.

The lower end of the standard section 15 which extends into the receptacle is received in a socket 22 formed in a cross bar 23. This cross bar is supported in U-shaped bearings on brackets 24 fixed on the end walls of the box 7. The cross bar 23 is provided with a pin 25 that extends into the socket 22 for a short distance, and that fits into a slot 26 formed in the lower end of the standard section 15 for fixing the position of orientation of the standard section.

An electric lamp 27 is mounted just below the standard and in line therewith, being supported in a tube 28 that is sealed in a water-tight manner to an annular flange 29 formed on the bottom of the box. The lamp is connected through suitable conductors 30 to a source of electrical energy.

The standard section 16 includes a lower end portion 31 adapted to fit snugly into the upper end of standard section 15 and a skirt portion 32 adapted to cover and surround the upper end of the standard section 15 so as to preclude any possibility of water entering the standard at the joint. The upper or exposed end of the standard section 16 is provided with a plurality of window openings 33 having window panes 34 held in place over them by suitable frames 35. Mirrors 36 are mounted in the standard section 16 in line with the window openings 33 and at a suitable inclination to reflect light from the lamp 27 out through the window openings along the roadway so that the attention of motorists will be drawn to the stanchion and danger of collision with it will be reduced. The mirrors are supported by lugs or fingers 37 bent inward from a sleeve 38 fixed in the standard section 16. The skirt portion 32 of standard section 16 is provided with a tooth 39 which interfits with a notch formed in the upper end of standard section 15 for fixing the position of orientation of the standard section 16.

Standard section 17 comprises a lower end portion 40 adapted to fit snugly within the upper end of standard section 16, a skirt portion 41 adapted to cover and surround the upper end of section 16, and an upper end portion 42 for supporting the indicator 4. The skirt portion 41 is provided with a tooth 43 adapted to interfit with a notch in the upper end of standard section 16 for fixing the position of orientation of the standard section 17.

The indicator 4 may be of any suitable form, but has been illustrated as a direction arrow such as is frequently employed. The indicator has affixed thereto a cap 44 which

is adapted to fit over and surround the upper end of standard section 42. The indicator 4 includes a finger or blade 45 that extends downwardly through the cap, and that has a flattened portion of a cylindrical stem 46 affixed to it. The cylindrical stem is adapted to fit snugly within the standard section 17. The finger 45 is not symmetrically disposed with reference to the cap, but extends into engagement with the skirt portion of the cap at one side while leaving space enough for reception of the wall of standard section 17 at the opposite side. Standard section 17 is provided with a plurality of slots 47 into any one of which the finger 45 may be fitted so as to fix the indicator in any one of a plurality of predetermined positions of orientation.

With a stanchion construction such as that described, it is not necessary to move the stanchion bodily to the side of the street at the end of the day, but the same may be disassembled into convenient units or sections and placed within the stanchion base which is sunk in the roadway. This, of course, involves removal of the lowermost standard section from the cover of the base. Provision is accordingly made of a sealing plug 48 adapted to be threaded into the opening 18 of the cover 8 and provided with an annular flange 49 adapted to fit in the circular channel 21 that is formed in the top of the cover.

It will be noted that in the form of the invention illustrated in Figures 1 to 6 and likewise in the form of the invention illustrated in Figures 7 to 10, provision is made for association of a plurality of standards and indicators with a single base. Only one of the standard and indicator assemblies has been described, however, since the other is a duplicate of it. The number of standards and indicators employed in connection with a given base might, of course, be increased, if desired, the construction and mode of operation being obvious from the embodiment of the invention already described.

In Figures 7 to 10 disclosure is made of another construction embodying features of the invention. This embodiment is generally like that of Figures 1 to 6 and will, therefore, be described relatively briefly, care being taken, however, to point out the features in which it differs from the embodiment of Figures 1 to 6.

The stanchion comprises a base 51 sunk in the roadway and comprises a box 52 and a cover 53 pivotally connected to the box by hinge pins 54. The standards 55 are not in this instance mounted on the movable cover 53, but are mounted on fixed cover sections 56 and extend through such fixed cover sections to the interior of the receptacle. Neither is provision made of a lamp within the receptacle, but instead, a lamp 57 is sup-

ported in the uppermost standard section in line with window openings 58 formed therein. The lamp has a flexible conductor 59 connected to it which is adapted to be let down through the other standard sections and into the receptacle, and which is provided at the lower end thereof with a plug 59a adapted to be inserted in a socket 60 mounted in the receptacle and connected in any suitable manner with a source of electrical energy.

The top faces of the walls of the box 52 are provided with channels 61, and passages 62 extend vertically downward from these channels through the box walls to conduct any water which reaches the channels to the ground without permitting access of the same to the interior of the receptacle.

The uppermost section 63 of standard 55 carries indicators 64, the indicators being placed against opposite sides of the standard section 63 and clamped firmly to it by means of bolts 65 and nuts 66. In this instance the standard section 67 next to the top section 25 may be provided with a plurality of notches 68 in the upper end thereof adapted to cooperate selectively with a tooth 69 formed adjacent the skirt portion of the uppermost section for determining various selected positions of orientation of the uppermost section, and hence of the indicator or indicators 64 carried by it.

At the upper end of the standard section 63 above the lamp 57 provision is made of a cap 70 which extends well beyond the lateral bounds of the window openings 58 and is adapted to protect them against ingress of water.

I have described what I believe to be the best embodiments of my invention. I do not wish, however, to be confined to the embodiment shown, but what I desire to cover by Letters Patent is set forth in the appended claim.

43 I claim:

In a traffic stanchion, in combination, a standard and a base, the standard being composed of separable sections adapted to be stored in the base, and the base comprising a box and fixed and hinged cover sections therefor, said fixed cover section being constructed to receive and operatively support the standard.

In testimony whereof I have affixed my signature to this specification.

MICHAEL J. McCUAUGHLEY.
